SIGN FLASHER

Clifford Hotchkiss, Elkhart, Ind., assignor, by
mesne assignments, to Minneapolis-Honeywell
Regulator Company, Minneapolis, Minn., a cor-
poration of Delaware

Application June 23, 1930, Serial No. 462,951

8 Claims. (Cl. 177—346)

This invention relates in general to sign flashers or the like and more particularly to sign flashers of the induction disc type adapted for use in controlling the operation of "speller" type signs.

- 5 One of the principal objects of the present invention is to provide a simple, compact and durable organization of an induction disc motor, gearing and mercury switches for controlling the operation of a speller type sign.
- 10 Another object of the invention resides in the provision of an organization of this character in which the speed of operation of the sign may be varied in an easy and convenient manner while maintaining the desirable sequence of the different phases of the cycle of operation.

15 Another object is to provide a sign flasher having these advantages and capacities and in which the gearing for effecting the varied operation of the several switch elements is enclosed and operates within the housing whereby it is protected against injury from dirt, dust, or the like, and may be run in a bath of grease or oil.

20 Other objects and advantages reside in certain novel features of the construction, arrangement and combination of parts which will be hereinafter more fully described, and particularly pointed out in the appended claims, reference being had to the accompanying drawings, forming a part of this specification, and in which:

25 Figure 1 is a view in side elevation showing Figure 1 is a view in side elevation showing a sign flasher embodying the present invention, parts being broken away and shown in longitudinal vertical section for the sake of illustration;

30 Figure 2 is a view of the sign flasher in front elevation with a portion of the front plate of the casing broken away to show the internal mechanism;

35 Figure 3 is a fragmentary view in front elevation showing a portion of the casing with its front plate removed to illustrate the gearing;

40 Figure 4 is a fragmentary view in elevation showing the underside of the front plate and the slotted crank arms;

45 Figure 5 is a view in section taken on line 5—5 of Figure 3 to further illustrate the gearing.

Figure 6 is a diagram of the electrical circuits involved in a typical installation;

50 Figure 7 is a diagram illustrating the flashing cycle; and

Figure 8 is a schematic wiring diagram of the electrical circuits of Figure 6.

55 Referring to the drawings, the numeral 1 designates a casing having a removable front plate 2 normally secured in position by screws 3. A

gasket 4 may be provided between the front plate and the adjacent portion of the casing to prevent leakage of grease from the casing or ingress of water, dirt, or dust thereinto.

5 At the lower end of the casing and at one of the upper corners thereof attaching brackets 5 and 6 are provided, these brackets being cast integral with the casing in the construction illustrated and having key-hole slots 5' and 6' adapted to coact with headed fasteners of the stationary support which may be the back wall of the box in which flashers of this type are usually installed.

10 Integral with one web of the bracket 5 is a seat or lug 10 (see Figure 2) to which the laminated core 11 of an induction disc motor designated generally at M is secured by screws 11'. The core 11 is of generally U-shaped form and one of its legs is surrounded by the field windings or coil 12, the terminals of which are connected by insulated flexible conductors 13 and 14 with binding posts 15 and 16 carried by a panel 17 of insulating material.

15 The panel 17 is supported by screws and spacer sleeves 18 and 18' on lugs 2' which may be formed integral with the front plate 2 of the casing. In the space between the legs of the laminated core 11, the rotor 20 of the motor M operates, this rotor being in the form of an induction disc. The upper end of one of the legs of the core 11 is provided with an inwardly extending lateral extension 11' and this extension and the upper end of the other leg constitutes the pole pieces of the field and are provided with shading coils 21 and 22 in the form of endless clips or plates of brass or copper set in notches in the pole pieces.

20 The rotor or disc 20 is fixed to one end portion of a motor shaft 23 supported for rotary movement in a bearing 24 formed in the back wall of the casing 1.

25 Within the casing 1, fixed supporting shafts 25 and 26 are provided, these shafts having their rearward ends tightly fitted and suitably secured in supporting bearings 27 and 28 formed on the back wall of the casing 1.

30 On the shaft 25 a large gear wheel 30 is mounted and meshes with and is driven by a pinion 29 fixed on the inner end of the motor shaft 23 (see Figures 3 and 5). The gear wheel 30 is fixed to a sleeve or bushing 31 (see Figure 2) rotatably supported on the shaft 25. A small gear 32 is also fixed to sleeve 31 and meshes with a large gear wheel 33 fixed on a sleeve or bushing 34 freely rotatable on the shaft 26 and having a small gear wheel 35 secured to its forward end.

35 This small gear wheel 35 carries a forwardly projecting crank pin 36. The teeth of gear 35 mesh 40 with the teeth of gear 30. The teeth of gear 35 mesh 45 with the teeth of gear 30. The teeth of gear 35 mesh 50 with the teeth of gear 30. The teeth of gear 35 mesh 55 with the teeth of gear 30.

with the teeth of a large gear wheel 37 rotatably supported on the shaft 25 and also carrying a forwardly projecting crank pin 38. With this arrangement the pinion 29 fixed to the motor shaft 5 drives the gear train made up of gear wheels 30, 32, 33, 35 and 37 so as to rotate the gear wheel 35 and its crank pin 36 at a much lower speed than that of the rotor of the motor and the gear wheel 37 at a still slower speed. The 10 ratio of gear wheels 35 and 37 in the construction shown, is such that the crank pin 38 rotates at one-half the speed of the crank pin 36.

These crank pins 36 and 38 are utilized for tipping mercury tube switches, one at twice the 15 speed of the other, and these switches are so organized in the lamp circuit as to produce a speller effect in the sign. For example, if the sign has its lamps arranged so that when all lamps are illuminated the sign will read 20 "John Doe" it will be operated with this sign 25 flasher so as to first flash the lamps forming the word "John", then flash the lamps forming the word "Doe" while holding on the lamps 30 forming the word "John", next, flash off all the lamps, then flash on all the lamps and finally 35 flash off all the lamps and then, of course, repeat the cycle.

In carrying out this purpose the crank pin 36 is engaged in the slot of a slotted crank arm 40 30 secured to the inner end of a switch operating shaft 41 supported in a bushed bearing 42 provided in the front plate 2. The forward end of the shaft 41 is formed with a reduced extension 43 and a shoulder 44 (see Figure 1). On the reduced extension 43 a switch operating arm 45 is supported and adjustably secured and at its lower end carries a clip or switch holder 46 in which a mercury tube switch 47 is secured.

The opening of the arm 45 is a free fit on the 40 reduced extension 43 of the operating shaft but this arm is held in any angular adjustment as well as against axial movement by means of a resilient clamping arm 48 secured at one end to the arm 45 by the same rivet employed for fastening the arm 45 to the switch clip 46 and having its other end notched and straddling the reduced extension of the switch operated shaft in between the shoulder 44 of this shaft and the arm 45. A washer 50 is fitted on the shaft and 45 clamped against the arm 45 by means of a nut 52. The resilient tensioning arm 48 is constructed so as to inherently tend to flex or bend and when compressed or bent back to the straight position shown in Figure 1, it puts the threads 50 between the nut 52 and the reduced extension 43 of the shaft 41 under tension thereby jamming or binding the nut against displacement and frictionally holding the arm 45 against angular displacement although permitting of ready 55 adjustment when the nut 52 is backed off.

Similarly, the crank pin 38 is interconnected with a slotted crank arm 60 fixed to the inner end of a switch operating shaft 61 supported in rocking movement in a bushed bearing 62 provided in the front wall of the casing. On this shaft 61 a switch operating arm 63 identical with the arm 45 is adjustably mounted in exactly the same manner as the arm 45 is mounted on its shaft. The arm 63 carries a switch clip 64 60 supporting a mercury tube switch 65.

As fully shown in the diagram (Figure 6) and as illustrated to some extent in Figures 1 and 2, one of the electrodes of the mercury switch 47 is connected by a flexible insulated wire 78 75 to the binding post 18. This binding post is elec-

trically connected to a binding post 71 connected to one side of the line 72. The other electrode of mercury switch 47 is connected by an insulated flexible conductor 73 with a binding post 74 electrically connected to a second binding post 75 which connects to a conductor 76 leading to a set of lamps designated at 77. The other side of the line designated at 78 is also connected to lamp 77 so that whenever the mercury in the switch 47 bridges its electrodes, the lamp 10 77 will be illuminated. The field coil 12 is constantly connected across the line by virtue of the connection of its terminals to binding posts 15 and 16, the binding post 16 being electrically connected to adjacent binding post 81, which, 15 in turn is connected by a wire 82 with the other side of the line.

A conductor 83 connects the wire 16 with a binding post 87 carried by an insulating panel 88 supported on the upper portion of the removable front wall 2 in much the same manner as the panel 17 is supported. This binding post 87 is electrically connected with a second binding post 89 of the panel 88 and the binding post 89 connects by a flexible insulated conductor 90 with one of the electrodes of the mercury switch 65. The other electrode of this mercury switch connects by a flexible insulated conductor 91 to a binding post 92 which is connected to a binding post 93 electrically connected to one end of a conductor 94 leading to the second bank or set of lamps designated at 95. The other side of the lamps 95 are constantly connected by a conductor 96 to the other side of the line designated at 78.

With this arrangement the high speed mercury switch 47 is a master switch and unless the mercury therein bridges its electrodes no current can flow to the lamps 95 even though the switch 65 be closed.

The on and off ratio adjustment is effected by first tipping or adjusting the high speed master switch 47 on its shaft 41 so that switch 47 will be on or closed about two thirds of the time and open or off about one third. The switch 65 45 is adjusted angularly with respect to its shaft so that it turns on or closes the circuit about half way between the first on and off of the master switch 47 and stays closed or on until after the master switch 47 turns off or opens the circuit 50 the second time.

As a result of this organization and adjustment of the switches and because of the driving of the switch 47 at twice the speed of the switch 65, the cycle of operation illustrated diagrammatically in Figure 7 may be had. Thus, as shown, the high speed master switch 47, when first closed, flashes the lamps 77, which, for example, may be arranged to spell the name "John". While the lamps 77 are still held on the switch 65 will close so that the lamps 95 (which may be arranged for example to spell the name "Doe") will flash. Then the switch 47 will open which extinguishes both sets of lamps. While the switch 65 still remains closed the switch 47, moving at the highest rate of speed, again closes and flashes both sets of lamps simultaneously. Next, both switches 47 and 65 are turned to the off position and the cycle of operation is repeated.

Variation of the speed of operation may be had by virtue of the organization of a magnetic drag with the induction disc motor. This magnetic drag is preferably in the form of a permanent magnet 100 having a frictional pivotal mounting on the casing and shiftable so that its poles may 70 75

straddle to the desired extent the periphery of the induction motor. By varying the degree of straddling the effect of the permanent magnet is regulated and the induction motor slowed up to the desired extent. Of course, this permanent magnet may be moved away from the rotor of the induction disc motor so that it will not have any appreciable effect thereon.

In accordance with conventional practice, a suitable switch is incorporated in the supply lines to the flashers to permit it to be thrown into and out of operation at will.

The invention claimed is:

1. In combination, an electric circuit, a source of current therefor, two sets of lamps connected in parallel in said circuit, a master switch incorporated in said circuit between one side of the source of current and both sets of lamps and having entire control of one of said sets of lamps, an auxiliary switch connected in series in said circuit between the master switch and the other set of lamps only whereby one set of lamps is energized solely under the control of the master switch and the other set of lamps is energized under the joint control of the master and auxiliary switches, and means for periodically opening and closing said switches at different periods.
2. In combination, an electric circuit, a source of current therefor, two sets of lamps connected in parallel in said circuit, a master switch connected in series in said circuit with both sets of lamps, an auxiliary switch connected in series in said circuit between the master switch and one set of lamps only, and means for opening and closing said master and auxiliary switches and maintaining the same open and closed for different periods whereby the lamps are flashed successively and simultaneously during an operating cycle.
3. In combination, an electric circuit, a source of current therefor, two sets of lamps connected in parallel in said circuit, a master switch connected in series in said circuit with both sets of lamps, an auxiliary switch connected in series in said circuit between the master switch and one set of lamps only, means for opening and closing said master switch periodically, and means for operating the auxiliary switch at a relatively lower speed and acting to move the auxiliary switch to closed position only while the master switch is closed and to open position only while the master switch is open.
4. A sign flasher comprising an electric circuit, a source of current therefor, two sets of lamps connected in parallel in said circuit, a master switch connected in series in said circuit with both sets of lamps, an auxiliary switch connected in series in said circuit between said master switch and one set only of said lamps, operators for closing and opening said switches, adjustable connections between the operators and the switches to variably relate the periods of "Off" and "On" of one switch with respect to those of the other switch, and means for actuating said

operators at different speeds, whereby the periods of one switch during a cycle of lamp operations alternately oppose and correspond with the periods of the other switch.

5. A device of the character described comprising an electric circuit, a source of current therefor, two sets of lamps connected in parallel in said circuit, a master switch connected in series in said circuit with both sets of lamps, an auxiliary switch connected in series in said circuit between said master switch and one set only of said lamps, and means for alternately moving the master switch to closed and open positions and for moving the auxiliary switch from open to closed position during the first and each successive odd numbered period that the master switch is closed and from closed to open position during the second and each successive even numbered period that the master switch is open.

10. A device of the character described comprising an electric circuit, a source of current therefor, two sets of lamps connected in parallel in said circuit, a single pole single throw master switch connected in series in said circuit with both sets of lamps, a single pole single throw auxiliary switch connected in series in said circuit between said master switch and one set only of said lamps, and means for alternately moving the master switch to closed and open positions and for moving the auxiliary switch to its closed position at approximately the middle 15 of the first period that the master switch is closed and to its open position during the last open period of the complete operating cycle of the master switch.

15. In combination, an electric circuit, a source of current therefor, two sets of lamps connected in parallel in said circuit, a master switch connected in series in said circuit with both sets of lamps, an auxiliary switch connected in series in said circuit between said master switch and one set only of lamps only, and means for causing alternate periods of the "Off" and "On" positions of said switches, said master switch having double the number of periods of said auxiliary switch, 20 said periods being so related that during the cycle of lamp operation said sets of lamps will successively light and then simultaneously flash "Off", "On", and finally "Off".

25. In combination, an electric circuit, a source of current therefor, two sets of lamps connected in parallel in said circuit, a master switch connected in series in said circuit with both sets of lamps, an auxiliary switch connected in series in said circuit between said master switch and one set of lamps only, means for opening and closing said switches, said master switch having a periodicity of operation greater than that of said auxiliary switch, said periodicity of each switch being correlated to effect a cycle of lamp 30 operation having a periodicity of operation greater than that of said master switch.

CLIFFORD HOTCHKISS.

CERTIFICATE OF CORRECTION.

Patent No. 2,000,700.

May 7, 1935.

CLIFFORD HOTCHKISS.

It is hereby certified that error appears in the printed specification of the above numbered patent requiring correction as follows: Page 3, second column, strike out lines 20 to 35 inclusive, comprising present claim 6; and lines 36 and 50, for the claim numbers appearing as "7 and 8" read 6 and 7 respectively; and that the said Letters Patent should be read with these corrections therein that the same may conform to the record of the case in the Patent Office.

Signed and sealed this 18th day of June, A. D. 1935.

(Seal)

Leslie Frazer, Acting Commissioner of Patents.
